(57) **CLAIM**

The ornamental design for a carton, as shown and described.

DESCRIPTION

FIG. 1 is a perspective view of a carton showing our new design;

FIG. 2 is a top planar view thereof;

FIG. 3 is a bottom planar view thereof;

FIG. 4 is a front elevational view thereof;

FIG. 5 is a rear elevational view thereof; and,

FIG. 6 is a left-side elevational view, the right-side elevational view being a mirror image thereof.
